UNITED STATES PATENT OFFICE

SAM WESTERHEIM, OF ST. PAUL, MINNESOTA

WINDOW CONSTRUCTION

Application filed May 5, 1930. Serial No. 449,993.

This invention relates to a window construction of that type including a vertically adjustable lower and upper sash, and has for its object to provide, in a manner as hereinafter set forth, a window so constructed and arranged to eliminate the employment of sash weights, sash cords and pulleys for retaining a sash in position when adjusted from normal.

10 The invention further aims to provide, in a manner as hereinafter set forth, a means other than sash cords, sash weights and pulleys for holding the sash or sashes of a window in position when adjusted from normal.

15 15 and with such means so constructed and arranged to provide a weather strip to exclude air, dust and moisture.

A further object of the invention is to provide, in a manner as hereinafter set forth, a 20 window construction including sashes and guide strips for the latter, and with the guide strips so constructed and arranged to provide a loose fit between them and the sashes whereby the sticking of the latter due to 25 warping or by collection of paint and varnish is prevented.

A further object of the invention is to provide, in a manner as hereinafter set forth, a 30 window structure including means to provide a complete insulation around the frame to prevent leakage and thereby overcoming leakage through the commonly used sash weight boxes.

35 A further object of the invention is to provide, in a manner as hereinafter set forth, a window construction to provide a complete insulation around the frame and further for retaining the sash or sashes in adjusted position without the employment of sash weights, sash cords and pulleys.

40 A further object of the invention is to provide, in a manner as hereinafter set forth, a window construction including means to set up a complete insulation around the frame and which can easily be applied and of a form to occupy minimum space.

45 Further objects of the invention are to provide, in a manner as hereinafter set forth, a window construction for the purpose referred to which is simple in its construction

and arrangement, strong, durable, compact, thoroughly efficient in its use, readily assembled, and comparatively inexpensive to manufacture.

With the foregoing and other objects in view the invention consists of the novel construction, combination and arrangement of parts as hereinafter more specifically described, and illustrated in the accompanying drawings wherein is shown an embodiment 55 of the invention, but it is to be understood that changes, variations and modifications can be resorted to which fall within the scope of the claims hereunto appended.

In the drawings wherein like reference characters denote corresponding parts throughout the several views:

Figure 1 is a sectional plan, broken away 60 of a window construction in accordance with this invention.

Figure 2 is a fragmentary view in perspective illustrating the guide strip and the suspending or holding means for the sashes in assembled relation.

Figure 3 is a section on line 3—3, Figure 1. 75

Figure 4 is a fragmentary view in perspective of the casing member.

Figure 5 is a fragmentary view in perspective of a sash suspending member.

Figure 6 is a fragmentary view in perspective of a holder member. 80

Figure 7 is a fragmentary view in perspective of the guide strip.

Referring to the drawings, the window frame is generally indicated at 1 and the latter has each side 2 thereof provided centrally of its inner face with a parting groove 3 of the desired depth. The groove 3 extends from the top frame member to the bottom frame member or sill of the window frame. 85

The top frame member is indicated at 4 and the sill at 5. The front and rear of the window frame have means indicated at 6, 7 respectively for confining in connection with the guide strips 8, 9 the lower and upper sashes 10, 11 respectively within the frame 1. The side stiles 12 of the sashes are spaced from the inner faces of the side members 2 of the frame 1. The means indicated at 6, 7 95 function as guides. The said means 6, 7 are 100

outer guides for the sashes 11, 10 respectively. The guide strips 8, 9 are the inner guides for the sashes 10, 11. The guide strips 8, 9 are common to the sashes 10, 11. The guide strips 8, 9 opposed the parting grooves 3 formed in the sides 2 of the window frame.

The window construction includes a pair of oppositely disposed casing members referred to generally at 13, 14 and each is positioned within a groove 3 and flanged to abut 10 against the inner face of a side member 2 of the window frame. The body of each casing member is of a depth less than the depth of the grooves. As the casing members 13, 14 are of like construction, but one will be described as the description of one will apply 15 to the other. Each casing member corresponds in length to the length of the groove in which it is mounted. Each casing member includes an inner wall 15, a pair of side walls 16, 17 and a pair of oppositely extending flanges 18, 19 which are disposed at right angles with the outer ends of the side walls 16, 17 respectively. The inner part of each 20 side wall is inset to provide a curved part 20 and a straight part 21, the latter merging into the inner wall 15 and the width of said inner wall is less than the width at the open end of the member. The inset parts of the 25 side walls 16, 17 are oppositely disposed. The casing member is of channel-shaped cross section and has its inner wall 15 provided with a set of lengthwise extending, oval-shaped slots 22. The inner wall 15 and side walls 16, 17 provide the body portion of the casing and which is disposed within the groove 3 and with the flanges 18, 19 of the casing positioned against the grooved inner face of a side member 2 of the window frame bordering 30 the sides of the groove 3. When the casing member is arranged in groove 3 the inner wall 15 thereof is arranged in spaced relation with respect to the inner wall of the groove and the outer parts of the side walls 16, 17 35 abut against the side walls of groove 3.

The width of the body portion of the casing member is such that the outer parts of the side walls 16, 17 will snugly engage the side walls of the groove 3.

50 The window construction includes a pair of oppositely disposed holder members of channel-shaped cross section. Each holder member is of a length corresponding to the length of the casing member. The holder members are generally indicated at 23, 24 and are of like construction, therefore but one holder member will be described, as the description of one will apply to the other. Each holder member includes a body portion 55 formed of an inner wall 25, a pair of side walls 26, 27 and a pair of oppositely extending flanges 28, 29 disposed at right angles to and formed integral with the outer ends of the side walls 26, 27 respectively. The inner wall 25 of the holder member is provided with

a set of spaced openings 30 adapted to align with the slots 22 formed in the inner wall 15 of the casing member. The width of the body portion of the holder member corresponds to the width between the inner faces of the 70 parts 21 of the side walls 16, 17 and the casing member. The body portion of the holder member is extended into the body portion of the casing member and the outer faces of the side walls 26, 27 of the holder member abut 75 the inner faces of the parts 21 of the side walls 16, 17 of the casing member. The flanges 28, 29 of the holder member oppose the flanges 18, 19 of the casing member. The purpose of the holder member will be presently referred 80 to.

The guide strips 8, 9 are of channel-shaped cross section and oppositely disposed with respect to each other. A guide strip is extended in and projects from the open end of a holder member. As the guide strips are of like construction, but one will be described, as the description of one will apply to the other. Each guide strip is open at its rear. Each guide strip includes an outer wall 31, a pair 90 of side walls 32, 33, and each of said walls is formed with an inner part 34, an intermediate part 35 and an outer part 36. The intermediate part 35 extends inwardly at right angles from the outer part 36 and merges 95 into the inner part 34 whereby the latter is inset with respect to part 36. The intermediate part 35 provides seats for a purpose to be presently referred to. The parts 34 are extended into a holder member and snugly 100 engages with the side walls of the latter. The parts 35 seat against the flanges of the holder member and the parts 36 are arranged exteriorly of the holder member. The parts 36 in connection with the wall 31 is positioned 105 between the inner faces of the sashes 10, 11 to constitute a guide therefor. A guide strip is carried by a holder member and bodily moves with the latter, as each holder member is spring controlled and shiftable relative 110 to a casing member.

A casing and a holder member are arranged relative to the passages 10, 11 in a manner whereby the two pairs of oppositely disposed flanges on said members will be interposed between a side stile of the sashes 10, 11 and a side member of the window frame. The pairs of flanges extend into the spaces 115 formed between the side stiles of the sashes and the sides of the window frame. The inner wall 31 and parts 36 of the side walls 32, 33 of the guide strips form a rectangular portion adjacent the flanges on the holder member and which extend between the sashes 10, 11.

120 Each holder member is slidably connected with a side of the window frame and is spring controlled and for this purpose holdfast devices, in the form of headed screws, 38 are employed and which extend through the 125

openings 30, slots 22 and are anchored in the sides of the frame. The screws 38 when anchored have the heads 39 thereof spaced from the inner wall 25 of the holder member and surrounding the shanks of the screws and interposed between the heads 39 and the wall 25 is a coiled controlling spring 40 normally tending to shift the holder member toward the side of the window frame, and further acting to shift the flanges of the holder member in a direction toward the flanges of the casing member.

Attached to each side stile of the sash is a resilient suspension member for the latter and which acts to detachably secure the sash in position when shifted from normal, that is to say, when the sash is adjusted to open position. The flanges at the outer ends of the side walls and the non-inset parts of the 20 side walls of the casing members provide tracks for the suspension members. The members 23, 24 provide holders for the suspension members as said members 23, 24 act to hold the suspension members against the 25 tracks provided by the casing members. As the suspension members are of like construction, but one will be described as the description of one will apply to the other. The suspension members are arranged in pairs and 30 the members of each pair are oppositely disposed. The members of each pair are connected to the sashes 10, 11. Each suspension member is formed of sheet metal of the desired gauge possessing a resilient characteristic and preferably is of a length corresponding to the height of the sash, but if desired, the length of the suspension members can be less than the height of the sash. The suspension members which are connected to the lower 40 sash are indicated generally at 41, 42 and the suspension members which are connected to the upper sash are indicated generally at 43, 44.

Each suspension member comprises an intermediate part 45, an outer part 46, an inner part 47, a pair of lengthwise extending flanges 48, 49 and a plurality of openings 50 provided in the outer part 46. The intermediate part 45 is disposed at an inclination relative to the parts 46, 47. The part 46 is outset with respect to the intermediate part 45 and the part 47 is inset with respect to the intermediate part 45. The flanges 48, 49 extend in opposite directions with respect to each other. The flange 48 in cross section is of greater length than the flange 49. The flange 48 projects rearwardly and is integral with the part 47. The flange 49 projects outwardly and is integral with the part 46. The flange 48 is positioned against the inner face of the non-inset part of the side wall of the casing member. The part 47 is positioned against the outer face of a flange of the casing member. The part 47 and flange 48 slide against a track provided by a flange and the

non-inset part of the side wall of a casing member. The part 46 is arranged against a stile 12 and the flange 49 extends into a groove 51 provided in the stile 12. Holdfast devices 42 secure the part 46 against the stile 12. 70 The part 44 is disposed at an inclination with respect to the stile 12. The part 47 has a close sliding fit with a flange of a casing member and is maintained in such position by a flange of the holder member. The 75 flanges of the holder members are spaced from the stiles 12.

The construction and arrangement of the casing members, holder members, guide strip forming members and suspension members 80 make a complete insulation around the sashes and functions as a weather stripping to exclude air, dust and moisture.

When a sash is elevated the pair of suspension members connected therewith will function to suspendingly secure the sash in the position to which it has been adjusted and which action is had by the controlling spring acting on the holder members and with the flanges of the holder members bearing against 90 the parts 47 of the suspension members in a manner to set up a frictional lock between the flanges of the holder members and the flanges of the casing members to hold the sash in its open position.

It is thought that the many advantages of a window construction, in accordance with this invention and for the purpose set forth can be readily understood, and although the preferred embodiment of the invention is as illustrated and described, yet it is to be understood that changes in the details of construction can be had which fall within the scope of the invention as claimed.

What I claim is:

1. In window construction of that type including an upper and a lower sash, the combination of two pairs of oppositely disposed resilient, vertically movable suspension members for the sashes, means for connecting the outer portions of said members to the side stiles of the sashes, oppositely disposed, spring controlled structures having parts thereof coacting with the inner portions of said members to provide a frictional latch for the latter, said inner ends of said members slidably positioned between said parts, and means for connecting said structures to the sides of the window frame.

2. In a window construction of that type including an upper and a lower sash, the combination of two pairs of oppositely disposed, resilient, vertically movable suspension members for said sashes, means for connecting the outer portions of said members to the side stiles of the sashes, oppositely disposed, spring controlled guide strip holding means and having coacting parts coacting with the inner portions of said members to form a frictional latch for the latter, said inner ends

of said members slidably positioned between said parts, and means for connecting said structures to the sides of the window frame.

3. In window construction of that type including an upper and a lower sash, the combination of a pair of oppositely disposed, oppositely lengthwise flanged spring controlled holder members of channel-shaped cross section for extension into and to project from the inner face of the sides of the window frame, a guide strip mounted in, extended from and seated against the flanges of each member, and means for connecting said members to the sides of the window frame.

4. In window construction of that type including an upper and a lower sash and a frame having the inner face of each side thereof provided with a groove, the combination of a pair of oppositely disposed, spring controlled holder members of channel-shaped cross section each provided with a pair of oppositely extending flanges opposing the inner face of a side of the frame, each member being mounted in and extended from a groove, a guide strip having a reduced inner portion extended in a holder member, the outer portion of the guide strip opposing the flanges of the holder member, and means for connecting the holder members to the sides of the window frame.

5. In window construction of that type including upper and lower sashes, the combination of a pair of vertically movable resilient suspension members for each sash and adapted to have their outer portions connected to the side stiles of a sash, and spring controlled, oppositely disposed structures adapted to be connected to the sides of the window frame and coacting with the inner portions of said members to provide a frictional latch therefor, the inner ends of said members being slidably mounted in said structures.

6. In window construction of that type including an upper and a lower sash, the combination of a pair of oppositely disposed casing members adapted to be seated in the sides of a window frame and each providing a pair of tracks, a pair of resilient, vertically movable suspension members for each sash and having their inner portions travelling on a pair of tracks, said suspension members being bodily movable with a sash, and a spring controlled, holder member extending into each casing member and adapted to be connected with the sides of the window frame and having means acting on the inner portions of said pair of suspension members and in connection with a pair of tracks providing a frictional latch for the suspension members to detachably secure a sash in its adjusted position when suspended.

7. In window construction of that type including an upper and a lower sash, the combination of a pair of inner guide strips for said sashes, said guide strips being formed

with intermediate seats, and two pair of oppositely disposed, spring controlled structures adapted to be secured to the sides of a window frame for bodily carrying said strips, said structure including oppositely extending flanges abutting said seats.

8. In window construction of that type including an upper and a lower sash, the combination of a pair of inner guide strips for said sashes, said guide strips being formed with intermediate seats, and two pair of oppositely disposed, spring controlled structures adapted to be secured to the sides of a window frame for bodily carrying said strips, said structure including oppositely extending flanges abutting said seats, said strips and said structures being of channel-shaped cross section.

9. In window construction of that type including an upper and a lower sash, the combination of a pair of inner guide strips for said sashes, two pair of oppositely disposed, spring controlled structures adapted to be secured to the sides of a window frame for bodily carrying said strips, and two pair of vertically movable sash suspension members, each pair being oppositely disposed and adapted to have their outer portions connected to the sashes, the inner portions of said suspension members slidably positioned within said structures, said structures having means to provide a frictional lock for said suspension members.

10. In window construction, the combination of a frame having the inner face of each of its sides formed with a parting groove, an oppositely flanged casing member of channel-shaped cross section positioned within each groove, an oppositely flanged holding member of channel-shaped cross section seated in and extending from a casing member, spring controlled means for each holder member, said means connecting the holder members to said sides, a guide strip positioned in and projecting from each holder member, two pair of oppositely disposed, vertically movable sash suspension members adapted to be connected to the window sashes, said suspension members positioned between the flanges of the holder members and the casing members and projecting in opposite directions from said holder and casing members, said spring controlled means coacting with the flanges of said holder and casing members to provide a frictional latch to maintain the suspension members in position to secure the sashes in adjusted position.

11. In window construction of that type including vertically movable upper and lower sashes, the combination of a pair of inner guide strips for and common to said sashes, said strips having their outer parts offset to provide intermediate seats, and spring controlled oppositely flanged holder structures for said strips adapted to be connected to the

sides of a window frame, said holder structures bodily carrying said strips therewith and having the flanges thereof abutting said strips.

- 5 12. In window construction of that type including vertically movable upper and lower sashes, the combination of a pair of oppositely disposed inner guide strips common to said sashes, each of said strips including
 10 an enlarged outer portion and a reduced inner portion, and a pair of oppositely disposed, spring controlled holder structures adapted to be connected to the sides of a window frame, the reduced portions of said strips
 15 extending into said structures, said structures bodily carrying said strips therewith.
13. In window construction of that type including vertically movable upper and lower sashes, the combination of two pair of suspension members for said sashes, each pair of suspension members being oppositely disposed, each suspension member having a flanged outer portion for connection to the side stiles of a sash, each suspension member
 20 having a flange at its inner portion and an inset inner end portion, and means adapted to be connected to the sides of the window frame and acting upon the inner end portions
 25 of said members to provide a frictional latch
 30 for the latter, the said inner flanges of said members being slidably positioned within said means.

14. In window construction of that type including vertically movable upper and lower sashes, the combination of a frame having the inner face of each side thereof formed with a parting groove, a channel-shaped casing extending into each groove and formed with oppositely extending flanges positioned
 35 against the inner face of a side of the frame, a channel-shaped holder member extending into each casing and provided with oppositely extending flanges opposing the flanges of the casings, means for connecting said members to the sides of a window frame and including controlling springs for said members, an inner guide strip extending into each member and bodily carried therewith, and a pair of oppositely extending, resilient, vertically movable suspension members having their inner portions connected to said casings and held against the casings by said holder members, said suspension members adapted
 40 to have their outer portions connected to the
 45 sashes.

15. In window construction of that type including an upper and a lower sash, the combination of a pair of oppositely disposed spring controlled structures adapted to be slidably secured to the sides of the window frame between said sashes, and a pair of inner guide strips for said sashes, each of said strips having a portion thereof loosely positioned within one of said structures, the other portion of each strip being enlarged
 50
 55

and positioned between said sashes, said structures being flanged, and the said enlarged portions opposing the flanges of said structure.

16. In window construction of that type including vertically movable upper and lower sashes, the combination of a frame having the inner face of each side thereof formed with a parting groove, a channel-shaped casing extending into each groove and formed with oppositely extending flanges positioned against the inner face of a side of the frame, a channel-shaped holder member extending into each casing and provided with oppositely extending flanges opposing the flanges of the casings, means for connecting said members to the sides of a window frame and including controlling springs for said members, an inner guide strip extending into each member and bodily carried therewith, and a pair of oppositely extending, resilient, vertically movable suspension members opposing the inner faces of the sides of the frame, having their inner portions extending into said casings, slidably held against the flanges of the casings, slidably held against the flanges of the casings by said holder members and adapted to have their outer portions fixed to the side stiles of said sashes.

17. In a window construction of that type including vertically movable upper and lower sashes, the combination of a frame having the inner face of each side thereof formed with a parting groove, a channel-shaped casing extending into each groove and formed with oppositely extending flanges positioned against the inner face of a side of the frame, a channel-shaped holder member extending into each casing and provided with oppositely extending flanges opposing the flanges of the casings, means for connecting said members to the sides of a window frame and including controlling springs for said members, an inner guide strip extending into each member and bodily carried therewith, and a pair of oppositely extending, resilient, vertically movable suspension members opposing the inner faces of the sides of the frame, having their inner portions extending into said casings, slidably held against the flanges of the casings by said holder members and adapted to have their outer portions fixed to the side stiles of said sashes, and said guide strips having enlarged outer portions bearing against the flanges of said holder members.

18. In window construction, a vertically movable sash suspension member comprising a lengthwise flanged outer part having apertures for the passage of holdfast devices to secure such part to a side stile of a window sash to bodily move with the latter, an intermediate part and a lengthwise flanged inner part, said intermediate part being inclined with respect to said other parts, the flange on the outer part extending in an

opposite direction with respect to the flange on the inner part.

19. In window construction, a vertically movable sash suspension member comprising a lengthwise flanged outer part having apertures for the passage of holdfast devices to secure such part to a side stile of a window sash to bodily move with the latter, an intermediate part and a lengthwise flanged inner part, said intermediate part being inclined with respect to said other parts, the flange on the outer part extending in an opposite direction with respect to the flange on the inner part, the cross sectional length of the flange on the inner part being greater than the cross sectional length of the flange on the outer part.

20. In window construction, a spring controlled supporting structure providing tracks for vertically movable sash suspension members and a support for an inner guide strip common to a pair of sashes, comprising a pair of channel shaped elements one nesting within the other, each of said elements being oppositely flanged at its mouth, the flanges of one of said elements opposing the flanges of the other of said elements, the sides of the outer element having a part thereof outset, the flanges of said elements and the offset parts of said outer element providing tracks for said suspension members and the flanges of the inner element providing seats for said guide strip, and a controlling spring bearing against said inner element for normally forcing it towards the outer of said elements.

21. In window construction, an inner guide strip for a sash, said strip being formed with intermediate seats, and a spring controlled oppositely flanged, sectional structure adapted to be secured on a side of the window frame for carrying said strip, said strip extending into said structure and having its seats bearing against flanges of the latter.

22. In window construction, an inner guide strip for a sash, said strip being formed with intermediate seats, and a spring controlled oppositely flanged, sectional structure adapted to be secured on a side of the window frame for carrying said strip, said strip extending into said structure and having its seats bearing against flanges of the latter, said strip and structure being of channeled shape cross section and oppositely disposed relative to each other.

23. In window construction, an inner guide strip for a sash, said strip being formed with intermediate seats, a spring controlled oppositely flanged, sectional structure adapted to be secured on a side of the window frame for carrying said strip, said strip extending into said structure and having its seats bearing against flanges of the latter, said strip and structure being of channeled shape cross section and oppositely disposed relative to

each other, and a resilient vertically movable suspension member slidably interposed between and projecting laterally from opposed sections of said structure and adapted to be connected to a window sash for bodily moving therewith, the said member providing a track and a frictional latch for said member.

In testimony whereof, I affix my signature hereto.

SAM WESTERHEIM.
